UNITED STATES PATENT OFFICE.

OSCAR W. TUCKER, OF LAGRANGE, GEORGIA.

SASH-LOCKING MECHANISM.

1,239,544.

Specification of Letters Patent.

Patented Sept. 11, 1917.

Application filed May 25, 1916. Serial No. 99,886.

To all whom it may concern:

Be it known that I, OSCAR W. TUCKER, a citizen of the United States, residing at Lagrange, in the county of Troup and State 5 of Georgia, have invented certain new and useful Improvements in Sash-Locking Mechanism, of which the following is a specification.

My invention relates to window locking 10 mechanism.

While the invention aims to generally improve, simplify and render mechanism of this nature more efficient and still maintain the cost of manufacture and upkeep at a 15 low figure, yet I particularly aim to provide mechanism of this nature including means mounted on a window sash to lock the companion sash and its supporting sash to the window frame against relative movement; mechanism of this nature including a securing device fastened to a window sash, a securing device fastened to a window frame and a locking bolt mounted from another sash and engageable with both of said securing 20 devices; and to provide a novel form of lock to coöperate with the securing devices and specifically one having a barrel, a bolt slidably mounted therein, a latch to maintain the bolt retracted against the action 25 of its urging spring and a means forming part of the barrel to mount the said latch, and to provide a device of the construction hereinafter set forth possessing the additional objects and advantages to be 30 pointed out in relation thereto as the description progresses, and which is to be taken in connection with accompanying drawings illustrating one preferred embodiment.

40 In said drawings:

Figure 1 is a view in front elevation showing a window having my improvements applied thereto;

Fig. 2 is a cross sectional view on an enlarged scale, taken on the line 2—2 of Fig. 1, and

Fig. 3 is a cross sectional view on the line 3—3 of Fig. 2.

Referring specifically to the drawings, a 50 window frame or casement is provided of which 4 is one of the side stiles. Mounted within the casement, are the usual upper and lower sashes 5 and 6 respectively which slide relatively as usual in a vertical plane.

55 A prime desideratum of the present invention is to provide a means whereby the

sashes 5 and 6 may be fastened against relative movement when in any position and to the frame of the window. To this end, a securing plate 7 is screwed as at 8 in a recess 60 provided in the stile 4. A second securing device is provided and is designated at 9, being fastened as by means of screws 10 to the inner side of a side stile 11 of the sash 5. As shown in the drawings, securing device 65 7 is provided with transverse recesses or slots 12 while the securing device 9 is provided with transverse slots or recesses 13, of the same width as the slots 12 and adapted to lie in the same planes therewith at different adjustments of the sash 5. A single fastening means, for instance the lock generally designated 14 may be provided on the lower sash 6 so as to engage both securing devices and thus fasten the sashes 5 and 6 in 70 75 desired relative positions and to the frame 4.

One specific construction of the lock 14 may be as follows: A rectangular hollow barrel or casing 15 is provided with end walls in which a bolt 16 is mounted for 80 movement slidably and longitudinally of the casing 15. This bolt has an abutment 17 thereon interiorly of the barrel and adapted to be engaged by an expansion spring 18 which engages one end wall of the casing 85 15 and surrounds the bolt. Normally the bolt at an arm 16^a projects into one of the slots 12 and at an arm 16^b into one of the slots 13 as seen in Figs. 2 and 3. A suitably shaped handle 19 is provided, if desired, on 90 the bolt 16 to facilitate its manipulation. Integral with the barrel 15 are tangs 20 through which screws 21 pass to secure the barrel to the top rail, or stile of the lower sash 6. The barrel 15 is closed at its top by 95 means of a shield 22 fastened to the barrel as by means of set screws 23. In order to maintain the lock bolt 16 retracted, the latch 24 is provided which is adapted to enter a notch or recess 25 in the bolt 16 and urged 100 into such position by means of a spring 26 fastened to the latch and engaging one of the tangs 20. The latch is pivoted at 27 by means of a set screw engaging a lug 28 integral with one end of the barrel 15.

When the sashes are to be adjusted relatively, lock bolt 16 is retracted, being held or maintained in such position by the engagement of latch 24 in the notch 25. It is clear that by sliding movement, as usual, the 110 sashes 5 and 6 may be moved to the desired relative position. At various adjustments

of the sashes, the slots 12 and 13 will lie in the same planes. In order to fasten the sashes at the adjusted positions, the latch 24 is swung out of engagement manually with the notch 25 whereupon the spring 18 urges the bolt 16 at arm 16^b into one of the slots 13 at arm 16^a into the slot 12 in the same plane therewith. Thus the sashes will be locked against relative movement and against 10 movement relatively to the frame 4. In order to accommodate relative movement of the sashes, where the securing device 9 projects beyond the stile 11, the sash 6 below the said securing device 9 may be cut away as is 15 obvious.

Since merely the preferred embodiment has been illustrated and described, it is to be understood that changes in the details thereof or may be resorted to within the spirit and 20 scope of appended claim.

I claim:

In a window sash lock, the combination of a barrel, a spring pressed sliding bolt

mounted in the barrel and projecting from either end thereof, oppositely projecting 25 arms carried by the one end of the bolt, the window sash having slots for the reception of the ends of the said arms, a latch pivotally mounted on one end of the casing, the said latch being spring pressed, the bolt 30 having a notch for the reception of the latch, a handle carried at the opposite end of the bolt to withdraw the arms from the slots, the said arms being integrally formed with the bolt and including a curved member 35 forming the forward arm disposed in a plane forwardly of the other arm, the latter projecting laterally at right angles in the opposite direction to the said first mentioned arm.

In testimony whereof I affix my signature 40 in presence of two witnesses.

OSCAR W. TUCKER.
